CLAIM

The ornamental design for a garment as shown and
described.

DESCRIPTION

FIG. 1 is a front perspective view of a garment showing my
new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The dash-dash broken lines depict stitching which forms no
part of the claimed design. The dash-dot-dash broken lines
that outline the partial human figure assists in illustrating
how the garment may appear when in a position of use and
forms no part of the claimed design. The dash-dot-dash
broken lines on the surface of the garment depict features of
the garment that form no part of the claimed design. The
dash-dot-dot-dash broken lines depict the bounds of the
claimed design and form no part of the claimed design.

1 Claim, 7 Drawing Sheets
